UNITED STATES PATENT OFFICE.

EDWARD M. HARVEY, OF EUGENE, OREGON.

LAMP-SHADE.

1,374,735.

Specification of Letters Patent.

Patented Apr. 12, 1921.

Application filed May 20, 1918. Serial No. 235,506.

To all whom it may concern:

Be it known that I, EDWARD M. HARVEY, a citizen of the United States, residing at Eugene, in the county of Lane and State of Oregon, have invented new and useful Improvements in Lamp-Shades, of which the following is a specification.

This invention relates to lamp shades or globes, and has for its primary object the provision of a globe equipped with an annular flange adjacent one end to accommodate a novel construction of means for attaching the globe to the top of an electric lamp.

15 In the accompanying drawings:—

Figure 1 is a vertical central sectional view of a globe or shade constructed and arranged in accordance with my invention and showing the same in use on an electric lamp.

20 Fig. 2 is a plan of the same with the electric lamp socket indicated in section and with the supporting collar of the shade shown in open position.

25 Fig. 3 is a similar view showing the supporting collar closed.

Fig. 4 is a detail elevation showing one end of the supporting collar and one side of the band.

30 Fig. 5 is a similar view showing the other end of the collar and the corresponding side of the band.

Fig. 6 is a sectional view showing a modified form of my improved globe and shade.

35 Fig. 7 is a fragmentary detail view of the globe showing the filler opening and closure therefor.

My improved globe which is indicated at 1 is made of any suitable size and shape, 40 is preferably pyriform and has an outer wall 2 and an inner wall 3 so that a chamber 4 is formed between the said walls, the said chamber being filled with perfectly clear water or with other suitable liquid. The

45 walls are jointed together around the neck or base of the globe as at 5 and the globe is formed with an exterior annular flange 6 around its neck. The connecting portion 5 of the globe, between the walls, is provided 50 with a filler opening 7 in which is a threaded socket or lining 8, a cap 9 being screwed in said socket or lining and forming a closure for the filler opening and adapting the globe to be readily supplied with the water

55 or other liquid and also enabling the water

or other liquid to be readily drained from between the walls of the globe.

Preferably, the inner wall 3 is formed at a point near the outer end of the globe with a flattened portion 10 which coacts with the corresponding portion of the outer wall and with the liquid therebetween to form a lens as will be understood. Hence the globe can be used for the purposes of a bull's eye lens and enables a powerful light to be directed 65 in any point desired without curtailing the light thrown out in other directions from the globe. The clear water or other liquid in the globe, between its walls, takes off the glare from the lamp within the globe and 70 renders the light soft and agreeable to the eye while yet powerful.

By the provision of the reflector, my improved globe is adapted for use not only for ordinary lighting purposes but also for 75 use as a headlight for an automobile or other vehicle. The liquid filler in the globe prevents glare and hence the use of a dimmer is unnecessary.

By placing coloring matter of any desired shade in the water with which the globe is filled the globe can be caused to produce a light of any desired color so that the globe is rendered very valuable for signaling and advertising purposes and is also 85 rendered extremely valuable for use by physicians in the bio-dynamo-chromatic method or the colored light method of diagnosing diseases.

In the form of the invention shown in 90 Fig. 6 the inner wall 3^a of the globe is formed with a flattened, or cylindrical side portion 3^b as well as with the flattened end portion 10^a.

Other modifications may also be made 95 within the scope of my invention.

In order to attach my improved globe or shade to the socket 11 of an electric lamp I provide a band 12 which is arranged around the neck of the globe and which bears 100 against the flange 6. I also provide a supporting collar 13 which comprises a pair of members 14 each of which has a semi-circular portion 15 and extended portions 16, 17. The ends 16 of the collar members are pivotally connected together by a pivot pin 18 which is bent as at 19 to pass outwardly over the flange 6 and is riveted or otherwise secured at its extremity as at 20 to one side of the band 12. At the opposite side of the 110

band is a substantially U-shaped keeper 21 which is pivotally connected thereto as at 22 and which is adapted to engage and lock the ends 17 of the collar together so as to 5 clamp the portions 15 of the collar around the electric lamp socket and to also secure the members 14 of the collar together to prevent casual disengagement of the collar from the socket. It will be understood that 10 the collar serves to suspend and to support the shade effectually and to position and retain the shade or globe concentrically with respect to the electric lamp bulb 23 therein.

While I have herein shown and described 15 a preferred embodiment of my invention, I would have it understood that changes may be made in the form, proportion and construction of the several parts, without departing from the spirit of my invention,

and within the scope of the appended claim. 20

Having thus described my invention, I claim:—

The combination with a shade having a circumferential flange around the neck, of a band surrounding the neck of the shade 25 and engaged under said flange, a finger secured to said band and curved over the edge of said shade, a pivot projecting from said finger, a pair of members having corresponding ends swingingly mounted upon 30 said pivot, means carried by said band for securing the opposite ends of said members together, and said members having intermediate bulged portions for the purpose specified. 35

In testimony whereof I affix my signature.

EDWARD M. HARVEY.
